TOOL

Elmer H. Fawley, Decatur, Ill., assignor to
 Mueller Co., Decatur, Ill., a corporation of
 Illinois

Application October 15, 1938, Serial No. 235,248

4 Claims. (Cl. 81—53)

This invention relates to tools for turning, to or from position, bodies such as corporation stops and the like.

The usual corporation stop, for example, comprises a body portion and nipples projecting in opposite directions from the body portion. One of the nipples is designed for engagement in a threaded aperture in a main while the other, the outlet nipple, is threaded for the purpose of receiving a coupling member. The body portion serves as a housing for a valve body which is ordinarily in the form of a tapered plug. In order to insert such a stop in a main, it has been the usual practice heretofore to thread a socketed tool on the outlet nipple, the two parts assuming a jammed relation upon rotation of the tool in the threading direction, so that the other nipple may be threaded into the main. Due to the jamming of the nipple in the socket of the tool, it frequently happens that the stop will follow the tool when it is attempted to remove the latter by reverse rotation. Furthermore, the coupling nipple is sometimes damaged during the operation. It is a purpose of the present invention to provide a tool which, while securely connected to the stop through the coupling nipple, does not rely on the latter for the transmission of torque, but positively engages the body of the stop so that rotation of the tool is directly transmitted to the stop body independently of the coupling nipple.

The invention will be described with reference to an illustrative embodiment of the tool as shown in the accompanying drawing.

In the drawing:

Figure 1 shows a stop in elevation, a portion of a main in transverse section, and the new tool in axial section.

Figure 2 is like Figure 1, but shows the parts of the tool in a different relation.

Figure 3 is an elevation of the stop and tool of Figures 1 and 2 as seen from a direction at right angles to the section plane of Figure 1, and

Figure 4 is a section substantially on line 4—4 of Figure 2.

Referring to the drawing, reference numerals 10 and 11 generally designate the stop and tool respectively. The stop comprises a body portion 12 which houses a plug 13, and as here shown, has opposite parallel side walls 14 and 15 parallel to the axis of the plug. The plug body has at one end a nipple 16 shown in Figures 1 and 2 as threaded in an opening in a main 17, and a nipple 18 which is the coupling nipple and which is engaged by the tool during the inserting or removal operation for the purpose of holding the tool and

stop together. At the base of nipple 18 is a shoulder 19, which, as here shown, is substantially square in plan.

The tool 11 comprises a shank portion 20 which is designed for engagement in the usual manner in the socket of a boring bar. At one end of the shank portion, and here shown as integral therewith, is a cylindrical head portion 21 which is provided with a cylindrical socket 22 coaxial with the shank portion. As here shown, the head portion includes diametrically opposite jaw portions 23 and 24 which project to an equal extent in the opposite direction from the shank portion and have opposed parallel faces spaced apart a distance slightly greater than that separating the side walls 14 and 15 of the stop body. The head portion is provided with parallel diametrically opposite axially extending slots 25 and 26 which extend into the jaw portions 23 and 24. The jaw portions are provided with diametrically opposite circumferentially extending grooves 28 and 29 and the wall of socket 22 has a circumferential groove 30.

Reciprocable in the head portion is an annular member 31 which has a threaded bore coaxial with shank portion 20 and designed for engagement with nipple 18. At diametrically opposite points pairs of studs 32 and 33 are threaded into member 31 and project into slots 25 and 26 respectively. Intermediate the pairs of studs member 31 is provided with an annular groove which receives an annular split wire 34 of spring metal which has an expansive action. When member 31 is in the position of Figure 1, where it is in the socket portion of the head, spring 34 engages in groove 30 so that the member 31 is yieldingly maintained in its inner limit of reciprocation. Member 31 is yieldingly maintained in its outer limit of reciprocation through engagement of spring 34 in the grooves 28 and 29. Studs 32 and 33 assist in guiding member 31 rectilinearly between its limits of reciprocation and also prevent relative rotation of member 31 and head portion 21, rotation of the tool being thus positively impalable to the stop. Also, the outer studs 32 and 33, through cooperation with the outer end walls of grooves 25 and 26, positively limit outward movement of the member 31 relative to the head portion. Inward movement of member 31 relative to the head portion may be positively limited by the inner studs 32 and 33 or by abutment of the member with the socket end wall.

Figure 1 shows the parts of the tool in the relation assumed when the tool is operatively engaged with the stop for either insertion or re-

moval. In this relation of parts member 31 is preferably entirely within the socket 22, and jaws 23 and 24 overlie faces 14 and 15 of the stop body and are adapted to engage the same to positively transmit rotation of the tool to the stop in either direction. Assuming that in Figure 1 the stop has just been threaded home and that it is desired to remove the tool, a pull is given to the shank 20 in a direction away from the stop so that spring 34 is forced out of groove 30 and the head moves relative to member 31 to the position shown in Figure 2 wherein spring 34 is engaged in grooves 28 and 29. The outer ends of the jaws are now substantially flush with the outer face of member 31. The jaws 23 and 24 are now in a position wherein they clear the faces of the stop body upon reverse rotation of the tool.

In initially applying the tool, its parts are in the relation shown in Figure 2. Member 31 is threaded on nipple 18 preferably to a relation wherein it is just free of abutment with shoulder 19 and with jaws 23 and 24 in such position that upon pushing the head portion of the tool toward the stop, the jaws will come to the operative position shown in Figures 1 and 3. The manner of application of the tool to the stop is the same whether the stop is to be inserted or removed, since rotation of the applied tool, Figures 1 and 3, is impartable to the stop in either direction.

It will be understood that the stop body need not have exactly the form shown and that the same applies to the jaw portions. It is only necessary that these parts be so formed that when the jaws are in the position of Figures 1 and 3, they will cooperate with some part or parts of the stop body so that rotation of the tool is positively transmittable to the stop without jamming of nipple 18 in member 31. Various changes in the form and relation of parts are possible without departure from the invention as defined in the following claims.

I claim:

1. A tool of the class described comprising a shank portion and a head portion at one end of said shank portion having a socket therein coaxial with said shank portion, said head portion including circumferentially spaced jaw portions projecting in the opposite direction from said shank portion and adapted to engage a body to be turned, said head portion having parallel axially extending slots extending into said jaw portions, a member axially reciprocable in said socket and along said jaw portions, said member having a threaded bore coaxial with said shank portion, and projecting means on said member engaged in said slots and cooperating with the latter to rectilinearly guide said member and to prevent relative rotation of said member and said head portion.

2. A tool of the class described, comprising a shank portion engageable with a boring bar, a radially expanded head portion at one end of said shank portion having a socket therein coaxial with said shank portion, the side walls of said head portion at the end of said socket remote from said shank portion being constituted as jaw portions, a member axially reciprocable in said socket and along said jaw portions between limit positions, said member having a threaded bore

coaxial with said shank portion, and means engaging said member with said jaw portions for preventing relative rotation when said member is within said jaw portions, said member when in the last-mentioned position being threadable on a nipple of a corporation stop or the like up to less than a jamming relation and without interference of said jaw portions upon turning said shank portion in threading direction, said shank and head portions being then movable relative to said member and stop to engage said jaw portions with the stop body so that further rotation of the tool will be imparted to the stop body by said jaw portions without jamming of said member and said nipple.

3. A tool of the class described comprising a shank portion engageable with a boring bar, a radially expanded head portion at one end of said shank portion having a socket therein coaxial with said shank portion, the side walls of said head portion at the end of said socket remote from said shank portion being constituted as jaw portions, a member axially reciprocable in said socket and along said jaw portions between limit positions, means for yieldingly retaining said member in its inner limit position, said member having a threaded bore coaxial with said shank portion, and means engaging said member with said jaw portions for preventing relative rotation when said member is within said jaw portions, said member when in the last-mentioned position being threadable on a nipple of a corporation stop or the like up to less than a jamming relation and without interference of said jaw portions upon turning said shank portion in threading direction, said shank and head portions being then movable relative to said member and stop to engage said jaw portions with the stop body so that further rotation of the tool will be imparted to the stop body by said jaw portions without jamming of said member and said nipple.

4. A tool of the class described, comprising a shank portion engageable with a boring bar, a radially expanded head portion at one end of said shank portion, having a socket therein coaxial with said shank portion, the said head portion including circumferentially spaced jaw portions projecting in the opposite direction from said shank portion and adapted to engage a body to be turned, a member axially reciprocable in said socket and along said jaw portions between limit positions, said member having a threaded bore coaxial with said shank portion, and means engaging said member with said jaw portions for preventing relative rotation when said member is within said jaw portions, said member when in the last-mentioned position being threadable on a nipple of a corporation stop or the like up to less than a jamming relation and without interference of said jaw portions upon turning said shank portion in threading direction, said shank and head portions being then movable relative to said member and stop to engage said jaw portions with the stop body so that further rotation of the tool will be imparted to the stop body by said jaw portions without jamming of said member and said nipple.

ELMER H. FAWLEY.
